UNITED STATES PATENT OFFICE.

WILLIAM GERWIEN, OF CHICAGO, ILLINOIS.

SPRING-HINGE.

SPECIFICATION forming part of Letters Patent No. 657,982, dated September 18, 1900.

Application filed March 2, 1899. Renewed February 10, 1900. Serial No. 4,823. (No model.)

To all whom it may concern:

Be it known that I, WILLIAM GERWIEN, a citizen of the United States, residing at Chicago, in the county of Cook and State of Illinois, have invented certain new and useful Improvements in Spring-Hinges; and I do hereby declare the following to be a full, clear, and exact description of the invention, such as will enable others skilled in the art to which it appertains to make and use the same.

This invention relates more especially to improvements in that class of spring-hinges that are termed "double-acting" and adapted for use in hanging doors that are capable of being opened in either direction from a common fixed center.

The object is to provide a device of this character that is simple in its construction, possessing great durability, not liable to get out of order, and to retain the door and jamb in their proper relative position with but little liability of being affected by constant use or from other causes.

Figure 1 shows a door and hinge in their closed position. Fig. 2 shows the same in their open position. Fig. 3 is a vertical section through the door and jamb on line 3, Fig. 5, looking in the direction indicated by the arrow. Fig. 4 is a horizontal plan section on line 4, Figs. 2 and 3. Fig. 5 is a transverse section on line 5, Fig. 3; and Fig. 6 is a detached detail of construction.

A may represent the broken-away part of a door, and A' the corresponding jamb part, to which the respective leaves of the hinge are attached. The stationary hinge-leaf B is rigidly secured to the jamb and the companion stationary leaf B' rigidly secured to the door. At their upper ends these companion hinge-leaves are connected by the intermediate movable hinge-plate B² and at their lower ends by the movable hinge-plate B³, which is the usual arrangement. In the present invention, however, the hinge-plates B² and B³ are of a concavo-convex shape, the object of which will be hereinafter described.

The jamb hinge-leaf B is provided between its respective ends with the cylindrical case B⁴, inclosing the torsion-spring C. The upper end of this spring-case is closed by a hub C' and the lower end by a corresponding hub C². The respective ends of the torsion-spring

are secured in the companion hubs, as at a, and when the door is opened in either direction the tension acts to automatically close the same. A rod C³ passes longitudinally through the open space in the center of the tension-spring and has the companion hubs mounted on the respective ends thereof, which forms a common connection therebetween and serves to hold the same in exact alignment. The free ends of the rod C³ stop short at a point just outside of the hubs and provide for the connection of the operating-arms.

One end of an arm D is mounted on the upper end of the rod C³. The connecting hinge-plate B² is provided on the convex side and lower end with a boss a', to which is attached one end of a common link D' by a pivot-pin a², which is in the vertical center of the hinge-plate B². The free end of this link is pivoted to the free end of the arm D, as at a³, Fig. 6, and forms the necessary operative connection. The arm D is provided with a lug a⁴, Fig. 6, through which is inserted a pin a⁵, adapted to engage with any one of a number of holes a⁶, formed in the hub C', by which arrangement the tension of the torsion-spring is regulated and operative connection between said hub and the arm D is made.

The hinge-plate B² pivotally connects the door and jamb leaves at their upper ends. The pintle a⁷ forms the pivoted connection with the door hinge-leaf and the pintle a⁸ with the jamb hinge-leaf. When the door is swung open in the direction shown in Fig. 2, the connecting hinge-plate B² remains stationary against the jamb, as the door hinge-leaf swings on the pintle a⁷. There being no movement of the connecting hinge-plate, the hub C' and the connecting-arm D and link D' also remain stationary, the torsion-spring being twisted at the lower end. In this position the convex side b of the hinge-plate B² is outward. When the door is swung in the opposite direction, the hinge-plate B² follows the movement of the door and turns on the pintle a⁸, which is on the opposite side of the door from that of the pintle a⁷, the hub C' and its connecting arm and link moving at the same time and twisting the spring from the upper end.

The construction and arrangement of the lower hinge connections are the same as the

corresponding upper parts and may be described as follows: One end of an arm D^2 is mounted on the lower end of the hub connecting-rod C^3 . To the free end of this arm 5 is pivotally connected one end of a link D^3 , the opposite end of which, Fig. 4, connects with a pivot-pin b' , inserted in the boss b^2 , formed on the convex side and upper end of the connecting hinge-plate B^3 . In this opening movement of the door, Figs. 2 and 4, the lower hinge-plate B^3 follows the movement of the door and presents the concave side b^3 outwardly, the boss b^2 on the convex side filling into the recess b^4 in the hinge-leaf B' . Opening 15 in the direction shown, the connecting hinge-plate B^3 turns on the pintle b^6 , and opening in the opposite direction the hinge-plate B^3 remains stationary against the jamb, the hinge-leaf B' turning on the pintle b^6 .
20 The arrangement of the connecting hinge-plates is such that they have an alternate action or movement, so that the relative position of the same is reversed in accordance with the direction in which the door is swung, 25 the moving hinge-plate acting on the spring, storing up the power necessary in automatically closing the door. By having the connecting hinge-plates of a concavo-convex shape it is possible to make the connecting 30 arms and links the same length and the pivotal centers the same distance apart, so that when the door is closed the joining ends of the connecting lever-arms and links are all in alinement with the hinge-knuckles and 35 present the finished appearance of the same, being mounted on the pintles connecting the hinges.

The hinge-leaves B B' are provided on opposite sides, top and bottom, with lugs d' d^2 —40 that is, two on each side of the door, the two on the same side being in a diagonal plane and having frictional contact with the knuckles d^3 on the connecting hinge-plates B^2 B^3 and forming a stop or check in preventing the door 45 from swinging too freely back and forth when

allowed to fly shut. These lugs will also ordinarily prevent the doors from being opened by the action of the wind.

Having thus described my invention, what I claim, and desire to secure by Letters Patent, is—

1. In a spring-hinge, the combination of the companion hinge-leaves, the connecting hinge-plates, of a concavo-convex shape, the tension-spring, the connecting-arms, and the connecting-links, said arms and links being of the same length, the links connecting with said hinge-plates on a line through the vertical center thereof.

2. In a spring-hinge, the combination with 60 a tension-spring, of a case, inclosing the same, the companion hubs, loosely inserted in the respective ends of said case, the rod connecting said hubs and having its free ends stop short outside thereof, the arms connecting 65 with the projecting ends of said rod, the connecting-links, and the concavo-convex hinge-plates.

3. In a spring-hinge, the combination with 70 the hinge-leaves, of the connecting concavo-convex hinge-plates, the links pivoted to said plates on a line through their vertical center, the arms, connecting with the free end of the links, the rod, on which the opposite ends of said arms are mounted, the tension-hubs 75 mounted on the respective ends of said rod, the case wherein are seated the reduced ends of said hubs and the tension-spring, inclosed therein having its respective ends secured in the tension-hubs.

4. In a spring-hinge, the door and jamb leaves provided on opposite sides with projecting lugs adapted to check any unnecessary swaying of the door.

In testimony whereof I affix my signature 85 in presence of two witnesses.

WILLIAM GERWIEN.
